UNITED STATES PATENT OFFICE.

CHARLES F. GREEN, OF SYRACUSE, AND GEORGE V. GREEN, OF FULTON,
NEW YORK.

DESIGN FOR AN IMPALING-PIN.

SPECIFICATION forming part of Design No. 26,507, dated January 12, 1897.

Application filed December 7, 1895. Serial No. 571,440. Term of patent 7 years.

To all whom it may concern:

Be it known that we, CHARLES F. GREEN, residing at Syracuse, in the county of Onondaga, and GEORGE V. GREEN, residing at Fulton, in the county of Oswego, State of New York, citizens of the United States, have invented and produced a certain new and useful Design for Tips for Impaling-Pins, of which the following is a specification.

In the accompanying drawings, which form a part of this specification, Figure 1 is an elevation of an impaling-pin, showing our new and original design for the tip thereof; and Fig. 2 is a vertical section through the tip.

In the drawings, A refers to the base of the impaling-pin, which forms no part of our invention.

B refers to the pin proper, the upper end of which is preferably flattened, as shown, while the main portion thereof may in cross-section be cylindrical, flat, winged, solid, or hollow, as we claim no invention in the shape of this portion.

C refers to the tip, which is preferably provided with a socket to fit the flattened upper end of the pin. The tip is intended for use upon various pins and the tip and pin for use upon various bases.

The tip is lance-shaped, being thin and broad at the middle portion and tapering 30 therefrom upwardly to a sharp point and downwardly to the pin upon which it is borne.

The tip has a depression or panel formed upon one side, substantially as represented at D, and in such panel a distinctive character or symbol may be located, if desired. 35

Obviously the panel D may be varied in outline and both sides of the tip may be provided with such panels and the tip may be secured to the pin in ways other than that 40 shown without departing from our invention.

We claim as our invention—

The design for the tip of an impaling-pin wherein said tip is lance shape in outline and has a panel or depression in its face, substantially as shown and described. 45

Signed at Fulton, in the county of Oswego and State of New York, this 28th day of November, A. D. 1895.

CHARLES F. GREEN.
GEORGE V. GREEN.
